ROCKING HORSE PLAYTHING

Clarence C. Holman, River Road, R.D. 2,
Lower Bank, N.J. 08215

Filed Feb. 18, 1971, Ser. No. 116,733

Term of patent 14 years

Int. Cl. D21—01

U.S. Cl. D34—15

FIG. 1 is a front perspective showing my design.
FIG. 2 is a side elevation, the elevation from the other side being identical but of opposite hand.

FIG. 3 is a rear elevation.

FIG. 4 is a top view.

FIG. 5 is a bottom view.

I claim:

The ornamental design for a rocking horse plaything, as shown and described.
